UNITED STATES PATENT OFFICE.

WALTER B. LASHAR, OF BRIDGEPORT, CONNECTICUT, ASSIGNOR TO AMERICAN CHAIN COMPANY, INCORPORATED, OF BRIDGEPORT, CONNECTICUT, A CORPORATION OF NEW YORK.

FOLDING-EXTENSION-HEAD LIFTING-JACK.

1,183,886.

Specification of Letters Patent. Patented May 23, 1916.

Application filed January 31, 1916. Serial No. 75,192.

To all whom it may concern:

Be it known that I, WALTER B. LASHAR, a citizen of the United States, and resident of Bridgeport, county of Fairfield, State of Connecticut, have made a certain new and useful Invention Relating to Folding-Extension-Head Lifting-Jacks, of which the following is a specification, taken in connection with the accompanying drawing, which forms part of the same.

This invention relates to screw or other lifting jacks specially intended for automobile service and to folding or loosely pivoted extension heads therefor whereby the extension head is permanently connected to the lifting head of the jack so as to be instantly raised to its operative position extending the effective height of the jack where alining members hold it firmly in alinement so long as the load acts thereon.

In the accompanying drawing showing in a somewhat diagrammatic way an illustrative embodiment of this invention, Figure 1 is an elevation partly in section. Fig. 2 is a partial elevation showing the extension head in lowered inoperative position; and Fig. 3 is an enlarged elevation showing the extension head in raised operative position.

The jack may comprise a frame 2 having a suitable base 1 secured thereto and having a lifting member comprising, if desired, the lifting screw 7 and a lifting head 8 which may be attached to the screw in any suitable way as by the screw or retainer pin 9. This lifting screw may coöperate with the nut 4 revolvably mounted in the frame and rotated by capstan bars or rods which may be inserted in the holes 24, for instance. Or the nut may be rotated by other suitable actuating connections from the endless operating chain 6, for instance, which as indicated may coöperate with the guide casing 3 swivelingly mounted on the shaft 5, these actuating connections being, if desired, in substantial conformity with the Lashar-Luce application 16,875 of March 25, 1915, which has matured into Patent 1,174,017 of February 29, 1916, and on which this invention is based, it being of course understood that the details of these actuating connections form no part of the present invention. If desired, the lifting head 8 may be formed with the recessed or curved seat 10 to more readily center and retain an axle or other member to be raised by the jack and the extension

head 12 permanently but loosely pivoted or connected with the head preferably engages it at separated points on both sides of the lifting screw, such as 18, 22, to more certainly secure definite bearing therewith in spite of the presence of dirt or the like which is apt to work into these parts under service conditions. For this purpose the central rib of this extension head may have its lower end 13 relieved or upwardly extended so as to prevent the possibility of any contact adjacent the center of the lifting head. It is desirable to have the extension head formed with a relatively narrow lifting seat 19 for which purpose the extension head may be upwardly tapered as indicated, this arrangement insuring the somewhat definite centering of the load coöperating with this extension head which correspondingly minimizes bending strains on the lifting screw or member which are of course more apt to be injurious when the lifting member is more fully extended under conditions when this extension head is brought into use.

The extension head may be permanently and loosely connected or pivoted to the lifting head as by loose pin and slot connections between the parts which may readily be effected by forming a slotted connecting lug 16 on the extension head located in a recess 14 in the lifting head which is preferably sufficiently narrow to give transverse guidance to this lug and thus contribute to the transverse alinement of the extension head when in raised operative position. As indicated in Figs. 2 and 3 the connecting pin 11 is mounted well within the lateral edge of the extension head which makes unnecessary any undesirable extension of this part, and the enlarged slot 15 with which this pin co-
operates is made ample so as to allow the radial as well as the pivotal movement of the extension head to sufficient extent to raise it from the lowered inoperative position shown in Fig. 2 to the raised operative position shown in Figs. 1 and 3.

Suitable alining means are preferably provided to insure the lateral alinement of the extension head so long as it is loaded and for this purpose the connecting lug 16 preferably closely engages the inner end of the recess 14 in at least some part as indicated in Fig. 3 so as to prevent any further movement of the extension head in that direction when it is in raised position as indicated in

Fig. 3. A suitable alining flange such as 21 may also be formed on a lifting head so as to be engaged by a flange or projection 18 on the extension head and prevent its rearward movement so long as the load is pressing this extension head downward. In this way the alinement of the parts under operating conditions is insured without any substantial interruption of the curved seat 10 of the lifting head and without depending on the strength of the connecting pin so that there is correspondingly less danger of distorting or breaking this relatively light pin. At the same time the parts are so loosely connected that the extension head may be readily raised as soon as the jack is withdrawn from the load and the extent of upward movement is roughly indicated by the dotted position of the extension head in Fig. 3. It is thus seen that the extension head can be raised so as to carry these alining members entirely out of contact and thus allow the extension head to be swung or folded over so as to bring it into the lowered inoperative position shown in Fig. 2 in which it is held by an alining projection 17 coöperating with the recess 14, for instance. In this position the extension head projects laterally to the minimum extent from the lifting member and is in fact located directly in line with the lifting member and frame, the shape of the extension head being relied upon to prevent undesirable interference with the lowering movement under these conditions.

This invention has been described in connection with a number of illustrative embodiments, forms, parts, proportions, materials, and arrangements, to the details of which disclosure the invention is not of course to be limited, since what is claimed as new and what is desired to be secured by Letters Patent is set forth in the appended claims:

45 1. In lifting jacks for automobiles and so forth, a supporting frame, a lifting member coöperating therewith and comprising a lifting screw and a connected lifting head provided with a recessed seat 50 to receive the load, an extension head permanently and loosely connected to said lifting head and being upwardly tapered and provided with a narrowed recessed lifting seat, said extension head having 55 separated supports to engage said lifting head adjacent its lateral portions, a slotted connecting lug on said extension

head extending into a recess in said lifting head and being transversely alined thereby, a connecting pin extending through said slot 60 to provide a permanent loose pin and slot connection for said extension head and alining means to insure the lateral alinement of said extension head and comprising an alining flange on said lifting head to prevent outward movement of said connecting lug when said extension head is loaded.

2. In lifting jacks for automobiles and so forth, a supporting frame, a lifting member coöperating therewith and comprising a connected lifting head provided with a recessed seat to receive the load, an extension head permanently and loosely connected to said lifting head and provided with a narrowed recessed lifting seat, said extension head having separated supports to engage said lifting head adjacent its lateral portions, a slotted connecting lug on said extension head extending into a recess in said lifting head, a connecting pin extending through said slot to provide a permanent loose pin and slot connection for said extension head and alining means to insure the lateral alinement of said extension head and comprising an alining flange on said lifting head to prevent outward movement of said connecting lug when said extension head is loaded.

3. In lifting jacks for automobiles and so forth, a supporting frame, a lifting member coöperating therewith and comprising a connected lifting head to receive the load, an extension head permanently and loosely connected to said lifting head by a loose pin and slot connection, said extension head having separated supports to engage said lifting head adjacent its lateral portions and alining means to insure the lateral alinement of said extension head when a load is acting thereon and comprising an alining flange on said lifting head.

4. In lifting jacks for automobiles and so forth, a supporting frame, a lifting member coöperating therewith and comprising a connected lifting head to receive the load, an extension head permanently and loosely connected to said lifting head, said extension head having separated supports to engage said lifting head adjacent its lateral portions.

WALTER B. LASHAR.
